TENT SLIP

Wood Sumner, Middlesex County, Mass., assignor to the United States of America as represented by the Secretary of the Army

Application May 12, 1954, Serial No. 30,446

Term of patent 14 years

(Cl. D54—11)

(Granted under Title 35, U. S. Code (1952), sec. 266)

To all whom it may concern:

The invention described herein, if patented, may be manufactured and used by or for the Government for governmental purposes, without the payment to me of any royalty thereon.

Be it known that I, Wood Sumner, a citizen of the United States and residing in the county of Middlesex and State of Massachusetts, have invented a new, original, and ornamental Design for a Tent Slip, of which the following is a specification, reference being had to the accompanying drawing, forming a part thereof.

I claim:

The ornamental design for a tent slip, substantially as shown.
